UNITED STATES PATENT OFFICE.

WILLIAM C. CARDWELL, OF RICE, TEXAS.

WIRE-STRETCHER.

SPECIFICATION forming part of Letters Patent No. 543,290, dated July 23, 1895.

Application filed April 2, 1895. Serial No. 544,165. (No model.)

To all whom it may concern:

Be it known that I, WILLIAM C. CARDWELL, a citizen of the United States, residing at Rice, in the county of Navarro and State of Texas, 5 have invented new and useful Improvements in Hand Implements for Constructing Wire Fencing, of which the following is a specification.

This invention has for its objects to provide 10 a novel, simple, economical, and effective hand implement or tool particularly designed for use in the construction of wire fences--as, for example, stretching the wires as they are being strung from post to post, taking up slack, 15 after the wires are strung, and drawing staples; to provide a new and improved combination implement or tool of such construction that quick short pulls can be exerted on the fence-wires by utilizing the fence-post as 20 the fulcrum for the implement or tool in using the latter as a lever to stretch the wires longitudinally from post to post, and to provide a simple hand implement or tool by which a single person can rapidly string the fence- 25 wires from post to post, stretch the wires, and kink or twist the same to take up slack.

To accomplish all these objects my invention consists in the features of construction and the combination of parts hereinafter described and claimed, reference being made to 30 the accompanying drawings, in which—

Figure 1 is a perspective view of my improved hand implement or tool; and Fig. 2 is a plan view of the same, showing the manner in which it is placed against a fence-post to 35 utilize the latter as a fulcrum in stretching the fence-wires.

In order to enable those skilled in the art to make and use my invention, I will now describe the same in detail, referring to the drawings, wherein—

The numeral 1 indicates a cylindrical shank having at one end a bifurcated head or claw 2, and at the opposite end lateral arms 3 and 4 of different length and projecting in opposite directions. The outer edges of the arms 4 and 5 are curved in such manner that the instrument is adapted to rest uniformly against a cylindrical fence-post, but the construction is such that if the post is square or any other shape in cross-section the arms 3 and 4 can rest upon the post for the purpose of stretch-

ing a wire, as will hereinafter appear. The shank, the claw, and the two heads are all formed in a single piece, and, preferably, the parts are of metal, although they may be of any material sufficiently strong for the purpose in hand. The shank is also formed integral at a point between the claw and arm 4, with a pair of laterally-projecting ears or lugs 5, between which a swinging stretcher-arm 6 is pivotally mounted through the medium of a pivot-pin 7. The outer end of the pivoted stretcher-arm is constructed with a fixed jaw 8, having a curved acting-face 9, 65 against which a fence-wire is adapted to be gripped through the medium of a pawl 10, pivoted to the arm 6 by a pivot-pin 12. The acting end of the pawl is curved and serrated, as at 13, in such manner that if a portion of a fence-wire is inserted between the curved face 9 of the fixed jaw 8 and the serrated face 13 of the pivoted pawl 10 the wire is gripped and can be stretched by placing the curved arms 4 and 5 of the shank 1 against a fence-post and swinging the shank in the arc of a circle, thereby utilizing the fence-post as a fulcrum in the use of the implement as a lever for stretching the wire longitudinally. The stretcher-arm 6 is curved downward, as 80 at 14, for the purpose of placing the rigid jaw 8 of the stretcher-arm in a plane below the arm 4 of the shank 1, so that when the lever is swung on the fence-post as a fulcrum the outer end portion of the stretcher-arm can be caused to pass beneath the curved arm 4 of the shank, and thus cause the stretched wire to lie directly against the outer face of the fence-post, as will be clearly understood by reference to Fig. 2. The wire 85 can then be secured to the fence-post by staples or other similar fastening devices. By this means the fence-wires can be strung from post to post, and prior to being stapled, nailed, or similarly secured thereto the wires can be 90 stretched longitudinally to give them the desired tension.

The outer extremity of the curved arm 3 is formed with a slot 15, which is designed to be used for kinking or twisting the fence-wire. In order to kink or twist a wire it is only necessary to insert the wire into the slotted end of the arm 3 and then swing the shank, the implement, or tool in the arc of a

circle to kink the wire, or one or more complete revolutions of the implement will twist the wire to the desired extent, for the purpose of taking up slack in fence-wires strung on 5 posts.

5 The bifurcated head or claw 2 is useful for drawing staples, nails, and similar fastening devices. To draw a staple it is only necessary to place the bifurcated head or claw over 10 the staple, force it behind the fence-wire, and then swing the implement, when the staple will be extracted.

15 The implement or tool described and shown is simple and economical in construction, and owing to the ease with which it can be manipulated, it is possible for a single person to rapidly string fence-wires from post to post, stretch the wires longitudinally to give the required tension between fence-posts, and to 20 kink or twist the wire at any time for the purpose of taking up slack.

25 The peculiar construction of the implement or tool enables it to be placed against a fence-post so that the latter constitutes a fulcrum in the use of the implement or tool as a lever for stretching the fence-wires. The construction is such that quick short pulls can be exerted on the fence-wires, and it is entirely unnecessary to brace the fence-post, which is 30 used as the fulcrum for the implement or tool in using the latter as a lever to stretch the wires.

35 In Fig. 2 of the drawings I have shown the implement as applied in use with a substantially round post, but it will of course be evident that it can be used with equal facility upon a post of any other contour.

Having thus described my invention, what I claim is—

40 1. A hand-implement or tool for constructing wire-fencing, consisting of a shank having at one end a bifurcated head or claw, and at the opposite end laterally projecting arms,

one of which is slotted to serve as a wire-kinker or twister, said shank being provided 45 between the bifurcated head or claw and the lateral heads with projecting ears or lugs, and a stretcher-arm pivoted to said ears or lugs, curved downward to pass under one of the lateral arms of the shank, and having at its 50 outer, unpivoted end a fixed jaw and a pivoted pawl for gripping a fence-wire, substantially as described.

2. A hand-implement for constructing wire-fencing, consisting of a shank having at one 55 end oppositely projecting arms 3 and 4 constructed of different length and curved between their extremities, one of the arms being slotted at its outer extremity to form a wire kinker or twister, and the other arm adapted 60 to lie against a fence post, and a stretcher-arm pivoted to said shank, curved downward to pass beneath one of the arms of the shank, and provided at its outer, unpivoted end with a rigid head and a pivoted pawl for gripping 65 a fence-wire, substantially as described.

3. A hand implement for constructing wire fencing, consisting of a shank provided intermediate its ends, with a bifurcated ear or lug, a downwardly curved stretcher-arm pivoted to said lug, and having its end bent in angular form, a pawl pivoted to the stretcher-arm and having its free end acting within said bent portion, and two oppositely projecting arms arranged upon one end of the 75 shank, the outer edges of said arms being curved in such manner that the instrument is adapted to rest uniformly against a cylindrical fence-post, substantially as described.

In testimony whereof I have hereunto set 80 my hand in presence of two subscribing witnesses.

WILLIAM C. CARDWELL.
